UNITED STATES PATENT OFFICE.

JAMES F. MAYFIELD AND HIRAM B. ALGER, OF LAKEVIEW, OREGON.

MEAT-CUTTING MACHINE.

1,080,875.

Specification of Letters Patent.

Patented Dec. 9, 1913.

Application filed October 5, 1911. Serial No. 653,077.

To all whom it may concern:

Be it known that we, JAMES F. MAYFIELD and HIRAM B. ALGER, citizens of the United States, residing at Lakeview, in the county of Lake and State of Oregon, have invented 5 certain new and useful Improvements in Meat-Cutting Machines, of which the following is a specification, reference being had to the accompanying drawings.

10 This invention relates to that class of machines for cutting meat, in which cutting blades revolve in proximity to a perforated plate, and the object of the invention is to provide a machine of this character in which 15 the necessity of special operations for sharpening said blades and the perforated plate will be avoided.

With the above and other objects in view, the invention consists of the novel features 20 of construction, combination and arrangement of parts hereinafter described, pointed out in the claim and illustrated in the accompanying drawings, in which,

25 Figure 1 is a longitudinal sectional view through the cutting machine and supporting base; Fig. 2 is a front view of the cutting blade; Fig. 3 is a sectional view on the line 3—3 of Fig. 1; Fig. 4 is a face view of the perforated plate; and Fig. 5 is a section 30 taken on the line 5—5 of Fig. 2.

Referring to the drawing, the numeral 1 designates a base having formed upon its upper end a pair of spaced supports 2, each of which are provided with boxings 3, the 35 purpose of which will be hereinafter described.

The cutter proper consists of a cylinder 4, having formed therewith a hopper 5, and through which meat or the like is fed to the 40 cylinder. The cylinder 4 is provided at its rear end with an annular flange 6, the same being adapted to rest against a similar flange 7 formed upon either of the supports 2, and bolted or otherwise suitably secured, 45 whereby the cylinder is supported in its operative position, and may be disconnected at any time to clean the same. The outer end of the cylinder 4 is threaded, and is adapted to receive a screw ring 8, by which 50 a perforated plate 9 is secured in its proper position. The plate 9 is provided with a central opening 10, in which the extension 11 of the feed screw 12 is journaled. The extension 11 is provided with a squared 55 portion 13, upon which is mounted the cutter 14. Formed integral with the inner end

of the feed screw 12 is a journal extension 15, the same being supported in one of the boxings 3, and being of sufficient length to project into the space formed between the 60 supporting arms 2, where it is fixed in the hub 16 of a belt pulley 17, by which motion is imparted to the said screw.

The interior of the cylinder 4 is provided with a series of spaced ribs 18, the side walls 65 19 of which are tapered to the same degree, so that the meat in the cylinder will be fed to the cutter 14 upon rotation of the feed screw with either right or left spiral ribs.

The cutter 14 comprises a hub 20, by 70 which the same is mounted upon the squared portion 13 of the journal extension 11 so that the same will be rotated during the rotation of the feed screw. Radiating from the hub 20 is a number of arms 21 each of 75 which is concave in cross section, and taper gradually toward their outer ends. Each arm is provided with cutting edges 22 and 23, the portion between said cutting edges providing bearing faces 24, which rest flush 80 against the inner face of the perforated plate 9. By forming the arms 21 concave in cross section the cutting edges 22 and 23 and bearing faces 24 are the only parts of the cutter which contact with the plate 9. By 85 tapering the arms 21 the cutting edges thereof are caused, during the rotation of the cutter, to create a draw cutting action upon the material, which naturally reduces the strain upon the operative parts of the machine, and at the same time effectually cuts the material.

Referring to Fig. 1 of the drawing it will be noted that a feed screw 25 is mounted in one of the supports 2 in a manner similar to 95 the feed screw 12, but ribs 26 thereon are so arranged as to feed the material toward the blade and plate upon the same being rotated, the only difference between said feed screw and feed screw 12 being the direction 100 in which the ribs are arranged, said feed screws both rotating in the same direction when power is imparted to the belt pulley 17.

From the foregoing description it will be 105 seen that when the cylinder 4 is in the position as shown in Fig. 1 of the drawing the cutter 14 is traveling in a reverse direction to that when the cylinder has been transferred to the other support 2 and in a position to permit the feed screw 25 to rotate 110 therein. While the rotation of the feed

screws 12 and 25 is at all times in the same direction, it is apparent that upon moving the cylinder from one to the other the direction of travel of the knife is reversed, but 5 the material being acted upon will be forced toward the cutter 14 and through the perforated plate 9, due to the fact that the spiral ribs upon the feed screws are arranged in opposite directions.

10 It is a well known fact that in machines of this type the cutting edges 27 of the perforations 28 formed in the plate 9 are worn or become dull by the constant travel of the cutter 14 in one direction only, and that the 15 cutting edge of the cutter at the same time becomes worn and dull. In the present invention the travel of the cutter is reversed when desired, so that when one of the cutting edges 22 is acting the cutting edges 23 20 are performing no function but at the same time are being sharpened when traveling against the inner face of the plate 9. Thus it will be seen that when the cutter is traveling in one direction certain of the cutting 25 edges are performing their proper function, while the other cutting edges are becoming sharpened, and at the same time the cutting edges and perforations 28 are being sharpened and worn equally, so that at all times to 30 produce a sharp cutting edge, which naturally facilitates a perfect cutting action, and obviates the necessity of removing the cutters and plates for re-sharpening and truing.

When it is desired to sharpen the cutting 35 edges of the blade 14 to impart a corre-

sponding action upon the inner face of the perforated plate 9 it is only necessary that the cylinder 4 be removed from one support to the other, whereby the travel of the cutter is reversed so that the cutting edges of the 40 perforations in the plate 9 will be sharpened and worn equally, which would not occur if the cutter was rotated in one direction at all times, as in the machines now in common use.

Having thus described the invention, we claim:

In a cutting machine, the combination of a perforated plate, a revoluble cutter having oppositely directed cutting edges arranged 50 to move both simultaneously in close proximity to said plate, means for revolving said cutter in either direction in proximity to said plate, and means for feeding the material to be cut past said cutter and through 55 said plate when said means is operated in the direction of one cutting edge and means for feeding the material to be cut past said cutter and through said plate when said means is operated in the direction of the other cutting edge.

In testimony whereof we hereunto affix our signatures in the presence of two witnesses.

JAMES F. MAYFIELD.
HIRAM B. ALGER.
